US00D847825S

(12) **United States Design Patent** (10) Patent No.: **US D847,825 S**
Coren (45) Date of Patent: ** May 7, 2019

(54) **DISPLAY SCREEN WITH GRAPHICAL USER INTERFACE FOR EMPLOYEE PROFILE**

(71) Applicant: **Alexandra Coren**, Miami, FL (US)

(72) Inventor: **Alexandra Coren**, Miami, FL (US)

(73) Assignee: **COREN INTELLECT LLC**, Milford, DE (US)

(**) Term: **15 Years**

(21) Appl. No.: **29/588,157**

(22) Filed: **Dec. 19, 2016**

(51) LOC (11) Cl. 14-04

(52) U.S. Cl.

USPC **D14/485**

(58) **Field of Classification Search**

USPC D14/485-495

CPC G06F 3/048-04897

See application file for complete search history.

(57) **CLAIM**

The ornamental design for a display screen with graphical user interface for employee profile, as shown and described.

DESCRIPTION

The sole FIGURE is a front view illustrating our display screen with graphical user interface for employee profile. The broken lines illustrate a display screen and form no part of the claimed design.

1 Claim, 1 Drawing Sheet
